[57] CLAIM

The ornamental design for a combined torch and magnifier, as shown and described.

DESCRIPTION

FIG. 1 is a rear perspective view of the combined torch and magnifier of the invention;

FIG. 2 is a front perspective view of the combined torch and magnifier of FIG. 1;

FIG. 3 is a right side view of the combined torch and magnifier of FIG. 1;

FIG. 4 is a left side view of the combined torch and magnifier of FIG. 1;

FIG. 5 is a top plan view of the combined torch and magnifier of FIG. 1;

FIG. 6 is a bottom plan view of the combined torch and magnifier of FIG. 1;

FIG. 7 is a front elevation view of the combined torch and magnifier of FIG. 1;

FIG. 8 is a rear elevation view of the combined torch and magnifier of FIG. 1;

FIG. 9 is a rear perspective view of a second embodiment of the combined torch and magnifier wherein the magnifier thereof is in an extended position;

FIG. 10 is a front perspective view of the combined torch and magnifier of FIG. 9;

FIG. 11 is a right side view of the combined torch and magnifier of FIG. 9;

FIG. 12 is a left side view of the combined torch and magnifier of FIG. 9;

FIG. 13 is a top plan view of the combined torch and magnifier of FIG. 9;

FIG. 14 is a bottom plan view of the combined torch and magnifier of FIG. 9;

FIG. 15 is a front elevation view of the combined torch and magnifier of FIG. 9; and,

FIG. 16 is a rear elevation view of the combined torch and magnifier of FIG. 9.
